UNITED STATES PATENT OFFICE.

EMIL G. JURGENS, OF CHICAGO, ILLINOIS, ASSIGNOR TO PETERS MACHINERY COMPANY, OF CHICAGO, ILLINOIS, A CORPORATION OF ILLINOIS.

PACKAGE-IDENTIFICATION APPARATUS.

Application filed October 10, 1921. Serial No. 506,623.

To all whom it may concern:

Be it known that I, EMIL G. JURGENS, a citizen of the United States, residing at Chicago, in the county of Cook and State of Illinois, have invented certain new and useful Improvements in Package-Identification Apparatus, of which the following is a specification.

My invention relates to improvements in package identification apparatus, and although of wide application is of particular service in connection with the identification of such packages, as cartons, in which are packed manufactured products subject to considerable variation in quality.

The principal objects of my invention are to provide mechanism for identification purposes which may be applied conveniently to existing types of machines used for packaging, which includes machines for forming the packages, for instance, cartons; to provide a construction in which the indicia applied to the package may be changed from time to time with convenience and dispatch; to provide a construction such that there will be substantially no interference with the operation of the packaging, including carton-forming mechanism; to provide a construction which may be quickly and conveniently adjusted, both as to its own operation and to conform with the operation of the main package-forming mechanism; to provide a construction which shall be simple and economical to design and manufacture, while being inexpensive and convenient to maintain and operate, and in general to provide an improved identification apparatus of the character referred to.

As illustrative of a preferred embodiment of my invention, I have shown the same as applied to a machine of the type shown in the United States patent to Frank M. Peters, No. 1,025,880, patented May 7, 1912.

In the drawings illustrating said application:

Fig. 1 is a side elevation of the identification apparatus and parts of the main Peters machine associated therewith,

Fig. 2 is a sectional plan view taken on the line 2-2 of Fig. 1, and

Fig. 3 is a plan view of a portion of a carton to which identification markings have been applied by my improved apparatus.

Referring to the drawings, 10 represents

the continuously moving conveyor chain of the patented carton-forming machine, said chain passing over an overhead constantly actuated horizontal shaft 11, said shaft being fitted with the usual sprocket wheel 12 around which said chain is trained. It will not be necessary for me to describe the operation of the forming heads 13 carried by said chain 10, as the function of said heads is adequately described in the said Peters patent. It will be sufficient to say that the machine receives suitably scored blanks 14, which upon descent of the heads 13, and in conjunction with other forming instrumentalities not shown, are formed up into open top cartons ready to receive bakery or other product.

The blanks 14 are fed into the machine horizontally in the direction of the arrow 15, the feeding movement being arrested by suitable stop members 16 and 17. Preferably my improved identification apparatus is installed on the machine adjacent to one of said stop members. To this end an opening 18 is cut in the bed plate 19 of the machine and the ordinary stop similar to 17 is replaced by a combination stop 16 and bracket plate 20, said bracket 20 serving as a support for the principal operating parts of the identification mechanism.

It will be observed that the bracket plate 20 is formed with a depending flange 21 and an extension 22, said extension 22 being apertured vertically to receive a type block 23. Said type block 23 is flanged or headed at its upper end as indicated at 24, in order that it may be securely and rigidly supported in the apertured extension 22, and in order to prevent it from moving due to vibration or other causes, I prefer to employ a small lock ball 25. The ball 25 is arranged to co-operate with a small recess formed as shown in the side of the type block 23 and is pressed into said recess by means of a small coil compression spring 26 seated in a horizontally extending opening bored in a small boss 27 on the end of said extension 22. A small screw plug 28 threaded into the end of said bore furnishes a backing for the end of spring 26.

The type block 23 is made with a vertically extending rectangular opening or channel therethrough, the bottom of which is closed by a stop plate 29 rigidly secured to the lower end of the type block. Said rec-

- tangular vertically extending opening accommodates a set of suitable steel type members 30 which co-operate with a hammer member 31, presently to be described more in detail. The end of the extension 22 and type block 23 constitute an anvil for the hammer 31, which on its descent impresses upon the under-side of the carton blank 14, markings corresponding with the type 30.
- 10 In the present instance, the type block is shown as being equipped with three type for marking the flap of a carton with the numerals 182. Said numerals 182 represent any desired identification data, for instance, the day or the year, a special batch or the product of a particular oven. The arrangement is such that the type may be quickly and conveniently changed whenever it is desired to change the data to be applied to the carton.
- 15 The hammer 31 is actuated as an incident to the operation of the main carton-forming mechanism and by the following mechanism. It will be observed that the bracket 20 is formed with an integral upwardly projecting lug 32, said lug being tapped to receive the threaded end of a stationary pivot pin 33. Said pivot pin 33 is locked securely in position by a nut 34 applied to the end 20 of the threaded portion of pin 33. The stationary pin 33 constitutes a fixed pivot for a rocking member, which is made with a pair of angularly disposed arms, the arm 34' serving as a holder for the hammer 31,
- 25 35 while the arm 35 controls the movement of the rocker. Said hammer 31 is mounted on the end of arm 34' by providing said hammer with a stem 36 extending through the end of arm 34' and secured therein by a back-nut 37.
- 40 Energy for actuating hammer 31 is supplied by a coil spring 38 which tends to pull said arm 34 downwardly at all times. One end of said spring 38 is hooked into an aperture 45 in extension 22, while the upper end of said spring 38 is hooked into an aperture 39 formed in the end of a tension regulating screw 40 threaded into an enlargement 41 of arm 34 and rigidly locked in position by 50 a nut 42.
- 45 The operation of the arm 34 under the influence of spring 38 is controlled by a cam 43 keyed to the shaft 11 and made in the form of a disk having cam notches 44 formed therein. Said cam notches 44 co-operate with a small cam roller 45 mounted on a pin 46 in the end of the upper arm 47 of a bell crank, said bell crank being oscillatably mounted on a fixed pivot pin 48. The 55 lower arm 49 of said bell crank is of considerably greater length than the upper arm 47, in order to multiply the amount of movement of the lower end of said arm 49. Said lower end is formed with a fork 50 which straddles a roller 51 rotatably carried by

a pin 52 seated in the upper end of the control arm 35 of the rocker.

In view of the above description, the operation of the hammer member 31 will be readily understood. Normally the concentric surface 52 of cam 43 maintains the parts in the position shown in Fig. 1 with the hammer 31 lifted out of operative position and against the action of spring 38. As soon however, as the movement of the shaft 11 75 brings the notch 44 into register with cam roller 45, the latter can drop into said notch and permit spring 38 to snap the hammer 31 down upon the anvil, thereby causing the type 30 to make an impression upon the under side of carton blank 14. As soon as the hammer has performed its marking function, the cam roller 45 rides up on the sloping portion 53 of notch 44 and causes the parts again to assume the position shown 80 in Fig. 1. It will be manifest that the cam 43 is so timed with reference to the carton-forming instrumentalities that when the hammer 31 strikes the anvil, carton blank 14 will be in position to receive the blow. 90

The above details of construction and operation being merely illustrative of a single application of my invention, it will be understood that the scope of same should be determined by reference to the appended 95 claims, said claims being construed as broadly as possible consistent with the state of the art.

I claim:

1. A carton-forming machine provided 100 with means for forming a carton from a single blank, an anvil member having marking devices on one face thereof and a hammer member co-acting with the operative face of said anvil to operate upon a portion 105 of the carton, said anvil member being equipped with changeable indicia, and means for actuating said hammer.

2. A carton-forming machine provided 110 with means for forming a carton from a single blank, an anvil member having marking devices on one face thereof and a hammer member co-acting with the operative face of said anvil to operate upon a portion of the carton, said anvil member being equipped 115 with changeable indicia, and means for actuating said hammer as an incident to the operation of the forming mechanism.

3. In a machine of the class described, the combination with means for forming a carton, of an impression member equipped with changeable indicia, and a spring-actuated hammer member co-acting with the operative face of said die member to mark said carton as an incident to the operation of said forming means. 120

4. In a machine of the class described, the combination with means for forming a carton, of a type block forming an anvil and equipped with changeable indicia, a hammer 130

member co-operating with said block, and means for actuating said hammer to cause the same to deliver a sharp blow upon said block to mark said carton as an incident to the operation of said forming means.

5. In a machine of the class described, the combination with means for forming a carton, of a die block forming an anvil and equipped with changeable indicia, and a 10 cam-controlled spring-actuated hammer co-operating with said block to mark said carton as an incident to the operation of said forming means.

6. In a machine of the class described, the 15 combination with mechanism for forming a carton, including means for advancing the blank, of means for applying suitable indicia

to the said blank during said advance, comprising a type block forming an anvil, a hammer disposed opposite to the operative 20 face of said anvil and adapted to deliver a sharp blow thereto as the blank passes therebetween, and means actuated by said carton forming-mechanism for actuating said hammer.

7. In a machine of the class described, an anvil member, a hammer member co-operating with said anvil member and movable relative thereto, changeable indicia in said anvil, a cam controlling the movement of 25 said hammer, and a spring for causing said hammer to deliver a sharp blow upon said anvil.

EMIL G. JURGENS.
